UNITED STATES PATENT OFFICE

2,681,068

APPARATUS FOR QUENCHING SEMICOKE

Daniel Petit, Paris, France

Application April 15, 1952, Serial No. 282,498

6 Claims. (Cl. 134—56)

1

This invention relates to apparatus for quenching coke. More specifically, the invention relates to apparatus for controlling the temperature of semi-coke resulting from the low-temperature distillation of coal.

Similar apparatus may be used for controlling the temperatures of other materials, such as shale or lignite which has been subjected to low-temperature distillation.

It is known that the semi-coke as it is discharged from the low-temperature distillation oven is readily ignitable.

In view of this, it is undesirable to place the coke in hoppers or trucks without first reducing its temperature to a desired safe limit which limit varies according to the circumstances.

The apparatus of the present invention assures that the temperature of the semi-coke immediately after discharge from the oven is reduced below that temperature at which the semi-coke is readily ignitable. This apparatus comprises a rotating chamber for semi-coke into which a quantity of water is introduced from a regulated liquid supply system. The chamber is disposed in an inclined position for gravity unloading of a charge from its lower end. The water supply is automatically controlled by the discharge temperature of the semi-coke. The temperature of the semi-coke is regulated by a thermocouple or another similar arrangement which regulates from a distance the introduction of water into the chamber. The vapors resulting from the quenching of the semi-coke are removed through a flue after having passed through a cyclone dust separator which separates the entrained dust. The rotating chamber may be of any desired shape in serving as a mixer into which the water is introduced.

The disclosed drawing is a vertical section of the apparatus schematically showing a suitable embodiment of the present invention.

Semi-coke is conducted by a conveyor 1 and a chute 2 into a hollow cylinder 3 rotated by a shaft 4, driven by a motor and gear means 5. The cylinder 3 is provided on the inner periphery with angle irons or iron plates 6 which serve as baffles to break up the semi-coke in such a manner as to assure its best contact with the water and also to facilitate escape of the resulting steam. This cylinder is disposed in an inclined position for gravity unloading of a charge from its lower end.

The water used for quenching the semi-coke is introduced into the cylinder through a nozzle 7 the rate of flow being regulated by regulator 55 connected to the liquid supply system.

2

8, controlled at a distance by a thermocouple 9, placed immediately below the semi-coke outlet of the cylinder. Upon its discharge from the cylinder, the semi-coke passes over this thermocouple, and the semi-coke is then collected by a conveyor 10. When the temperature of the semi-coke at the outlet side of the cylinder rises, the thermocouple 9 actuates the regulator 8 and the amount of water introduced at 7 is increased accordingly.

On the other hand, if the amount of water is more than necessary to give the proper temperature to the semi-coke, the thermocouple temperature is reduced and the amount of water introduced at nozzle 7 into the cylinder is decreased accordingly.

The vapors escape through a cyclone dust catcher 11 where dust is removed before the vapors are discharged into the atmosphere through a chimney 12.

20 I claim:

1. Semi-coke quenching apparatus for quenching semi-coke from a low temperature distillation oven comprising a rotating chamber disposed in an inclined position for gravity unloading of a charge of semi-coke from its lower end, a liquid supply system communicating with said chamber and adapted to feed liquid to said chamber, and means for automatically regulating the flow of liquid to said chamber in accordance with the discharge temperature of the semi-coke.

2. Semi-coke quenching apparatus for quenching semi-coke from a low temperature distillation oven comprising a rotating chamber disposed in an inclined position for gravity unloading of a charge of semi-coke at its lower end, a liquid supply system communicating with said chamber and adapted to feed liquid to said chamber, means for automatically regulating the flow of liquid to said chamber in accordance with the discharge temperature of the semi-coke, and means to remove dust from the vapors escaping from said chamber.

40 3. The quenching apparatus of claim 1, in which said rotating chamber for semi-coke comprises a hollow cylinder with baffle plates attached to and extending continuously lengthwise from end to end along the inner periphery of the cylinder for dispersing the semi-coke and to facilitate escape of the resulting steam.

4. The quenching apparatus of claim 1, in which said means for automatically regulating the flow of liquid to the chamber comprises a

and a thermocouple connected to the regulator and positioned at the semi-coke outlet side of the chamber.

5. Semi-coke quenching apparatus for quenching semi-coke from a low temperature distillation oven comprising a hollow cylinder with baffle plates attached to the inner periphery of the cylinder for dispersing the semi-coke, said cylinder disposed at an inclined position for gravity unloading of a charge of semi-coke at its lower end, a liquid supply system communicating with said chamber and adapted to feed liquid to said chamber, a regulator connected to the liquid supply system and a thermocouple connected to the regulator and positioned at the semi-coke outlet side of the chamber for automatically regulating the flow of liquid to the chamber, and a cyclone dust catcher positioned near the cylinder for removing dust from the vapors escaping from said cylinder.

6. In combination with a semi-coke conveying means leading from a low-temperature distillation oven, a semi-coke quenching apparatus

comprising a rotating inclined chamber having its upper end communicating with said conveying apparatus and its lower end adapted to unload said coke that is gravity fed thereto, a liquid supply system communicating with said chamber and adapted to feed liquid to said chamber, and means for automatically regulating the flow of liquid to said chamber in accordance with the discharge temperature of the semi-coke.
